CLARENCE W. CROOKSHANK, OF SAN DIEGO, CALIFORNIA, ASSIGNOR, BY DIRECT AND MESNE ASSIGNMENTS, TO BOTTLE TOPS, INC., A CORPORATION OF DELAWARE

CAP FOR BOTTLES

Application filed December 26, 1928. Serial No. 328,574.

My invention relates to caps for bottles and other containers and method of producing the same and the objects of my invention are: first, to provide a cap of this class which may be securely fastened over the opening of a bottle or other similar container and which may be readily removed therefrom without the necessity of a bottle opener or other similar instrument, which openers or other instruments are not always at hand when desiring to remove the caps from bottles or other similar containers; second, to provide a cap of this class having a means intermediate its edge to permit ready insertion of a cap prying member therethrough for prying the cap from bottles, but which cap is of such construction as to thoroughly seal the normal open end of the bottle or other container; third, to provide a cap of this class through which any small rigid instrument, such as a knife, fork, nail, piece of wood or the like, may be inserted for prying off the cap; fourth, to provide a cap of this class having an opening at its middle portion and a gasket at its inner side and means for sealing the opening which is of lesser strength than the body of the cap, which sealing means may be readily removed or forced through the opening for inserting the cap prying-off member through the opening for prying off the cap from the bottle or other container; fifth, to provide as a whole a novelly constructed cap of this class; sixth, to provide a cap of this class with a relatively weak portion intermediate its edge adapted to receive the end of an instrument for releasing the pressure and removing the cap; seventh, to provide a cap of this class which is very simple and economical of construction, durable and which will not readily deteriorate or get out of order; eighth, to provide a novel method of producing a cap for bottles or other containers; ninth, to provide a novel method of making a cap for bottles and other containers which cap has a relatively weak portion intermediate its edge for receiving an instrument for releasing the pressure and removing the cap; tenth, to provide a novel method of making readily removable caps for bottles and other containers, and eleventh, to provide

a method of this class which is very simple and economical of operation, efficient and practical.

With these and other objects in view as will appear hereinafter, my invention consists of the certain novel features of construction, combination and arrangement of parts and portions and the certain novel method of producing caps of this class as will be hereinafter described in detail and particularly set forth in the appended claims, reference being had to the accompanying drawing and to the characters of reference thereon which form a part of this application in which:

Figure 1 is an enlarged plan view of a fragmentary portion of cap material with the first operation, that of making an opening in the preferred form in the material; Fig. 2 is a sectional view through 2-2 of Fig. 1; Fig. 3 is a plan view of the same after it has been rolled down smooth, the next step in the act of manufacture; Fig. 4 is a sectional view through 4-4 of Fig. 3; Fig. 5 is a plan view of the same after the opening or incision has been filled with the sealing material; Fig. 6 is a sectional view through 6-6 of Fig. 5; Fig. 7 is a top or plan view showing a sheet of metal and showing how the caps are stamped from the sheet of metal at the same time producing the open or weakened portion intermediate the edge; Fig. 8 is a sectional view of a fragmentary portion of the cap on an enlarged scale after it has received the sealing material and before being crimped on the bottle top; Fig. 9 is a sectional view through the middle of the cap complete with the gasket and bottle top which is shown fragmentarily; Fig. 10 shows a modified form of opening in the cap from the other views of the drawing; Fig. 11 is another modified form, and Fig. 12 is another modified form.

Similar characters of reference refer to similar parts and portions throughout the several views of the drawing.

The cap is made as follows: Suitable sheet material 1, preferably metallic, is used, preferably in strips of about the size of the cap in its finished form, as shown best in Fig. 7

of the drawing. Punched near the center in spaced relation, as shown in Fig. 7, are openings, preferably as shown in Fig. 1 of the drawing, but they may be as shown in Figs. 10, 11 or 12, or any similar opening; it being noted that the one shown in Fig. 1 is only punched through a portion of the circle forming arcuate slits 2 and leaving a weakened portion 3 to complete the circle, all as shown best in Figs. 1 and 2 of the drawing. The metal is then rolled out pressing the cutout portion flat, as shown in Figs. 3 and 4. Due to the stretching of the material when punching out in the first operation, the rolling in the second operation practically closes the slit, as shown best in Figs. 3 and 4 of the drawing. The metal is then tinned or covered with a coating of tin, thereby completely closing the slits 2. Thus the tinning operation performs two functions, one of covering the cap with a preserving coating, the other of filling the slit with a relatively weak material so the same may be easily fractured with an instrument for relieving the pressure in the bottle and providing means for readily removing the cap.

It will be noted that after the surface is tinned there is left a slight depression outlining the weak portion of the cap so that it is easy to locate the weak portion from the exterior of the finished product. It being noted that the tinning being very thin and relatively weak, it is easily broken, thus the circular portion formed by the slits 2 may be easily separated from the remaining portion of the cap to form an opening.

The next step consists in stamping the material in circular pieces and crimping the edge to form a bottle cap, as shown in Figs. 8 and 9 of the drawing.

The next step is in crimping the cap in position on the bottle in the conventional manner, after which it is as shown in Fig. 9 of the drawing in completed form, the usual gasket, preferably cork, forming a seal between the cap and the top of the bottle covering the entire surface of the cap.

It will be here noted that if desired the material may be tinned before punching or after it is punched and before rolling. This, however, will form a weaker seal than that formed by the preferred method, as the metal then is merely pressed together instead of forming a continuous layer over the slits 2 which is not so satisfactory.

In the modified forms shown in Figs. 10, 11 and 12, the openings instead of being circular are in varying forms, for instance, Fig. 10 shows a V-shaped opening, Fig. 11 an X-shaped opening, and Fig. 12 a slotted opening, all of which might be utilized if desired using the same process and producing substantially a like cap structure.

Though I have shown and described a particular method of producing caps for bot-

70 tles and other containers and certain modifications thereof, and a certain cap for bottles and other containers with certain modifications thereof, I do not wish to be limited to the particular method nor the particular modifications thereof, nor to the particular cap or the particular modifications thereof, but desire to include in the scope of my invention the method and cap structure substantially as set forth in the appended claims. 75

Having thus described my invention, what I claim as new and desire to secure by Letters Patent is:

1. In a cap for bottles adapted to contain effervescent beverages, a metallic shell having a securing portion at its outer edge, a slotted opening intermediate its edge, a sealing gasket member secured on the inner side of said shell over said opening and a preservative metallic covering for said cap filling the slits therein. 80

2. In a cap for bottles adapted to contain effervescent beverages, a metallic shell having a crimping securing portion at its outer edge shaped to be crimped over the outer side 90 of a bottle top, a slotted opening therein with one outer extremity spaced some distance inwardly of the inside of the bottle opening for receiving a pointed instrument for removing the cap, and a preservative covering for said cap filling the slotted opening therein. 95

3. In a cap for bottles and other containers adapted to contain effervescent beverages, a metallic shell having a securing portion at its outer edge and an opening intermediate its edge, a sealing gasket member positioned on the inner side of said shell and over said opening, and a tinning covering for said cap filling the opening therein and sealing the same. 100

4. In a removable cap for containers, a rigid metallic shell having a securing means at its edge and intermediate the edge a weakened portion considerably smaller than the container opening leaving a shoulder adapting the portion defined by the weakened portion to receive a pointed instrument and be forced readily inwardly thereby for removing said cap and a protective coating over and filling the weakened portion. 115

5. In a cap for bottles adapted to contain effervescent beverages, a metallic shell having a crimping securing portion at its outer edge shaped to be crimped over the outer side of a bottle top, a slotted weakened portion centrally therein, a sealing gasket member secured on the inner side and covering the inner side of said shell, and a preservative covering on the outer surface of said cap and filling the slotted weakened portion thereof. 120

In testimony whereof, I have hereunto set my hand at San Diego, California, this 5th day of December, 1928.

CLARENCE W. CROOKSHANK.
